UNITED STATES PATENT OFFICE

OSCAR J. KAY, OF LOS ANGELES, CALIFORNIA, ASSIGNOR TO GENERAL WATER HEATER CORPORATION, OF LOS ANGELES, CALIFORNIA, A CORPORATION OF DELAWARE

DESIGN FOR A WATER HEATER

Application filed December 22, 1930. Serial No. 38,066. Term of patent 3½ years.

To all whom it may concern:

Be it known that I, OSCAR J. KAY, a citizen of the United States, residing at Los Angeles, in the county of Los Angeles, State of California, have invented a new, original, and ornamental Design for Water Heater, of which the following is a specification, reference being had to the accompanying drawing, forming a part thereof.

I claim:

The ornamental design for a water heater, as shown.

Signed at Los Angeles, California this 10th day of December, 1930.

OSCAR J. KAY.
